UNITED STATES PATENT OFFICE.

ROBERT HENRY ROARK, OF WACO, TEXAS.

ICE-SCORING MACHINE.

Application filed June 30, 1923. Serial No. 648,815.

This invention relates to improvements in ice scoring machines, and in the form herein described is applied to a machine having mechanism for scoring a block of ice longitudinally and transversely to define a plurality of units or sections, any desired number of which may be easily broken off by the retail dealer, the scoring not only facilitating the division of the block into small pieces which are uniform and marketable, but also insuring the delivering of an accurate amount without requiring weighing.

The device disclosed in the present application comprises an improvement over the invention defined in my earlier application filed August 24, 1922, Serial Number 584,075.

It sometimes happens that in a machine of this type, the blocks of ice are not accurately placed on the conveyor, or become slightly displaced during their progress through the machine, so that they stick or are thrown out of proper alinement with the saws resulting in inaccurate scoring and possibly in damage to the machine. Then too, the blocks of ice vary somewhat in thickness, and this increases the difficulties of accurately guiding the same through the machine.

One of the important objects of the present application is to provide suitable means for guiding the block of ice through the machine, in which provision is made for receiving blocks of varying thickness, as well as blocks which have been inaccurately presented to the machine, and for arranging and guiding them in such a manner with relation to the saws that the scoring will be effected in a uniform manner and without jamming.

A further object of the invention is to provide a frictional connection between the source of power and certain operating parts of the machine, so that in case the saws encounter a foreign substance, or in case any other condition arises to interfere with the smooth and easy operation of the machine, this connection will slip and permit the working parts to stop without injury to any portion of the machine.

With the above advantages in view, the invention consists in the construction, combination and arrangement of parts which will be more fully described in connection with the accompanying drawings, which illustrate one way in which these improvements may be accomplished.

In the drawings:

Figure 1 is a perspective view of the machine with the present invention installed thereon.

Figure 2 is a plan view of the same.

Figure 3 is a horizontal section showing particularly the improved guiding means.

Figure 4 is a transverse section on the line 4—4 of Figure 2.

Figure 5 is a sectional detail view of the frictional connection.

Referring more particularly to the drawings, I have illustrated a machine comprising an elongated rectangular frame 10 through which the cake of ice is conveyed, and which consists of any desired arrangement of longitudinal and transverse main bars, and any desired number of upright or other auxiliary bars, which may be found necessary to support the bearings and other elements of the mechanism. At the bottom of the frame there are provided longitudinal skids or tracks 11, on which the block of ice A is supported during its passage through the machine. These skids extend from the entrance end 12 of the machine to a point approximately at the center thereof, and the block of ice is conducted onto these skids in upright position by any desired means.

Journalized in suitable bearings at one side of the entrance end of the frame are a pair of vertical shafts 13 and 14, which carry sprockets 15, about which are trained feed chains 16 provided with prongs or teeth 17 adapted to engage against one rear edge of the successive blocks of ice for conducting them through the machine. The upper end of the shaft 13 carries a bevel gear 18 meshing with a gear 19 on a countershaft 20 journaled at the top of the frame 10 near the entrance end, and carrying a pulley 21, and journaled upon the top of the frame near the intermediate portion thereof is a shaft 22 carrying a pulley 23, about which is trained a belt 24, which drives the pulley 21. Also secured on the shaft 22 is a pulley 25, which is operatively connected by a belt 26 with a pulley 27 secured to a horizontal transverse shaft 28 journaled at the top of the frame near the outlet end of the machine. Any suitable source of power may be used for rotating the shaft 28 to drive the above described mechanism and the other mechanism to be hereinafter described, though a convenient arrangement is to employ an electric motor 29 mounted on the frame, the shaft of which carries a pulley 30 operatively

connected by a belt 31 with a pulley 32 secured to the shaft 28.

The blocks of ice during the first part of their passage through the frame 10 are scored transversely by means of a plurality of opposed saws 33 carried by vertical shafts 34 journaled in suitable bearings at the sides of the frame, and driven from the shaft 22 by means of intermeshing bevelled gears 35 and 36 carried respectively by the shafts 22 and 34.

As soon as the block of ice passes the saws 33, it is delivered to a tilting cage 37 carried by trunnions 38 journaled in the sides of the frame. This tilting cage has one side and one end open for receiving the cake of ice in upright position, and delivering the same in longitudinal position after the cage has been tilted. In order to effect this tilting movement, one of the trunnions 38 has an upstanding lever 39 rigidly secured thereto and actuated by means hereinafter described for tilting the cage periodically in timed relation with the conveying mechanism. The cage 37 is so balanced with relation to the trunnions 38, that it normally rests by gravity in the position shown in Figure 1, and when it is tilted the block of ice A is delivered to inclined tracks or skids 40, which are located at the outlet end of the machine.

To effect this tilting movement of the cage to its discharge position, I provide a shaft 41 journaled at the top of the frame in rear of the shaft 22 and carrying a bevel gear 42, which meshes with a bevel gear 43 secured to the upper end of the shaft 14. Secured to one end of the shaft 41 is a sprocket wheel 44, which is operatively connected by a sprocket chain 45 to an idler sprocket 46 journaled at one side of the frame. The chain 45 travels between the lever 39 and the adjacent side of the frame, and carries a lug 47 designed to engage the lever at the proper time to tilt the cage upon its trunnions. The ratio of the different pulleys, which form this part of the transmission mechanism is important, as the movement of the feed chains 16 and chain 45 must have such a relation that the successive blocks of ice will be conducted through the machine, and forced into the cage 37 in timed relation to the tilting movement of the latter.

The means for effecting the longitudinal scoring of the blocks consists of a plurality of saws 47 secured to shafts 48, which are journaled in suitable bearings at the outlet end of the machine, and are slightly inclined so as to be perpendicular to the plane of the skids 40. The shafts 48 have bevel gears 49 secured to their upper ends meshing with bevel gears 50 on the shaft 28 by means of which they are driven.

The improved means which I have pro-

vided, is adapted to receive blocks of varying thickness, and to guide the same accurately in relation to the saws 33, so that the latter may score the block transversely without jamming, and without the block becoming displaced, and includes a plurality of guides arranged longitudinally at the sides of the passageway through the machine, at least one of the guides being yieldable so as to vary its distance from the other guide, and thus maintain a position in yielding engagement with the surface of the block, whatever its thickness. In the present embodiment of the invention, as will be seen from Figures 3 and 4, I have provided intermediate side rails 51 and 52, which are rigidly secured to the sides of the frame and spaced apart sufficiently to provide ample width for the thickest block of ice which may be presented. At one side of the frame above the rail 51, and near the upper end of the block of ice to be received, I have provided a guide 53, which in the present case is rigidly secured to the frame, while at the opposite side of the machine I have provided a guide 54 rigidly secured to the front end of the side of the frame opposite the guide 53, and having a resiliently held rear end portion 55, which is normally held in the passageway in the path of the block of ice as shown in Figure 3, so that the block will be firmly and accurately held and guided, and yet the portion 55 will yield outwardly when engaged by the ice.

The invention also includes a frictional driving connection arranged somewhere between the source of power and certain operating parts of the machine, so as to permit said parts to stop, in the event that any unusual obstruction is encountered, without causing injury to the machine. In the present exemplification of this feature, the pulley 23 is loosely mounted on the shaft 22, and provided at one side with a female clutch member 56, adjacent to which is a male clutch member 57 keyed to the shaft as shown at 58, and adapted to be urged into frictional engagement with the member 56 by a coiled spring 59 acting between said member 57 and a washer 60, which is limited in its outward movement by a pin 61. A plurality of openings 62 may be provided or the washer 60 may be replaced by a washer of different thickness in order to adjust the tension of the spring 59 and consequently the amount of friction between the members 56 and 57, so as to obtain the desired result. By this construction, as shown, when any unusual obstruction is encountered, the clutch and the chain 16 will slip, and consequently the block of ice will remain stationary. When the machine is functioning in a proper manner, however, the friction between the parts 56 and 57 will be sufficient to properly operate the machine.

It will be understood of course that the structure by means of which the improved results are obtained is not limited to the precise form herein described, and that any 5 equivalent means may be used for guiding the block of ice that will prevent the same from tipping or wedging as it is conveyed into contact with the saws. At least one of the guides, however, should be yieldable, but 10 should have sufficient tension to press firmly against the side of the block of ice in order to hold the same against displacement while it passes the saws.

What is claimed is:

15 1. In an ice scoring machine, a frame having two longitudinally disposed guides spaced apart in a common horizontal plane and adapted to receive a block of ice between them, one of said guides being held rigid, 20 the other having a front portion rigidly held in parallel relation to the rigid guide, and a rear portion which is resiliently held and normally closer to the rigid guide than is the front portion, whereby to urge the block of 25 ice against the rigid guide as said block of ice passes rearwardly, an endless traveling element having a prong which projects inwardly beyond the rigid guide to engage the block of ice and convey it rearwardly be-

tween said guides, and means for scoring the 30 ice as it is so conveyed.

2. An ice scoring machine comprising, in combination, a frame, a trackway over which blocks of ice may be slid therethrough, a mechanical conveyor for feeding blocks of 35 ice over said trackway, vertically spaced scoring means arranged on the sides of the frame, and longitudinal guide members secured to the inside of the frame; one of said guide members having a resilient portion 40 projecting inwardly between the frames adapted to engage the blocks of ice and press them firmly against the other guide member during their transit between the scoring means. 45

3. An ice scoring machine comprising, in combination, a frame providing a trackway for blocks of ice arranged on end, a plurality of vertically spaced and oppositely arranged scoring saws on the side of said frames, a 50 mechanical conveyor to convey the blocks between the scoring saws, a rigid longitudinal guide on one side of the frame and a resilient guide on the opposite side of the 55 frame between the scoring saws.

In testimony that I claim the foregoing as my own, I have hereto affixed my signature.

ROBERT HENRY ROARK.
